ABSTRACT: A ship is described which is useful for recovery of liquid minerals from the ocean floor. A rotatable plug through an aperture in the ship's hull is moored to the ocean floor with a riser pipe from the ocean floor passing through the center of the plug and connected to a substantially vertically extending tower above the ship to permit the ship to "weather-vane." The tower, supporting the upper end of the riser, rotates with the ship, and vertical translation of the upper end of the riser relative to the length of the tower is permitted. The tower is mounted on gimbals near its base for tilting relative to the deck of the ship to remain aligned with the riser end. A tube connected to the tower extends below the gimbals and surrounds the riser. Rollers at the lower end of the tube engage the riser to permit longitudinal motion of the tube relative to the riser, and transfer some of the tilting force between the riser and the tower. The tube is rotatable about its axis to remain fixed relative to the riser while the ship rotates.

RISER SUPPORT STRUCTURE

BACKGROUND

In the offshore production of oil and other subaqueous fluid minerals there is a practical depth limitation for bottom mounted towers that extend above the surface. This practical limit is in the order of about 600 feet and economic considerations may limit the utility of towers to even shallower depths. An alternative to fixed towers is to provide a portion of the production facilities on the sea floor and provide a permanently moored floating facility for the balance. When this is done a substantially vertically extending conduit or riser must be provided between the sea floor and the floating facility. In relatively shallow depths and calm waters many of the problems of permanently interconnecting a floating facility and the sea floor have been solved. Thus, for example, a flexible hose may be provided between the ship and the bottom, however, when the depths become great the stresses involved are too large for a conventional flexible hose and relatively rigid pipes are employed. In such a system the stresses between a moored ship and relatively rigid riser become significant due to roll, pitch and heave of the ship relative to the riser.

SUMMARY OF THE INVENTION

Thus there is provided in practice of this invention a fluid-carrying riser having its upper end connected to a ship by means of a tilttable tower. A riser guide aligned with the tower extends along a portion of the riser for minimizing the stresses on the riser. The riser guide is mounted so as to be rotatable relative to the tower about an axis extending along the riser.

DRAWINGS

35

Objects and many of the attendant advantages of this invention will be readily appreciated as the same becomes better understood by reference to the following detailed description when considered in connection with the accompanying drawings wherein;

FIG. 1 illustrates in perspective cutaway a portion of a ship and underwater riser with a tower for accommodating pitch, roll and heave of ship;

FIG. 2 illustrates in partial longitudinal section a riser guide tube and its mounting; and

FIG. 3 illustrates an end view of the bottom of the guide tube.

Throughout the drawings like reference numerals refer to like parts.

DESCRIPTION

This invention relates to an aspect of an interconnection between an underwater riser and a floating ship. Other aspects of the interconnection between the riser and ship are described, illustrated and claimed in copending U.S. Pat. applications Ser. No. 838,489, filed July 2, 1969 entitled, "Underwater Riser and Ship Connection" by George W. Morgan; Ser. No. 838,435, filed July 2, 1969 entitled "Permanent Ship Mooring System" by Bruno R. Naczkowski, and Ser. No. 838,489, filed July 2, 1969 entitled "Oil Production Vessel" by George W. Morgan and Bruno R. Naczkowski, all of which were filed on the same date as this application are assigned to North American Rockwell Corporation, assignee of this application and the contents of which are hereby incorporated by reference for full force and effect as if set forth in full herein.

The general relation of a ship and its parts and a riser incorporating the principles of this invention are illustrated in FIG. 1. As illustrated in this embodiment a ship 10 is moored to the ocean floor by a plurality of anchor chains 11 each of which is connected to a mooring plug 12 extending vertically through the ship. A mooring plug is mounted on bearings 15 so that the ship may rotate relative to the mooring plug which is substantially fixed in position relative to the ocean floor. Additional

bearing, *seriatim*, a constant tension load is applied to the upper end of the riser 13. The nature of a constant tension winch is to apply a constant tension to the cable wound thereon irrespective of the cable position. Thus as the ship may rise or fall, for example and the upper end of the riser remains in a substantially fixed position, the draw bar 28 will ride up and down the side rails of the tower and more or less cable 39 is paid out or withdrawn, as required, by the constant tension winch 38. With this arrangement a constant tension is applied to the upper end of the riser throughout the extent of any excursion of the riser end along the length of the tower.

As mentioned hereinabove as the ship pitches or rolls the substantially fixed upper end of the riser causes the tower 23 to tilt relative to the ship. In order to minimize the stresses on the riser at the location of the tower gimbal mounts, that is, the spherical member 21 below the tower base, the riser guide tube 24 is provided. The guide tube 24 is attached to the spherical member 21 and extends downwardly therefrom substantially to the lower end of the mooring plug or swivel 12. Thus both the tower 14 and the guide tube 24 are rigidly secured to the spherical member within the gimbal mounting so as to remain in alignment. That is, the tower and guide tube are essentially a single elongated rigid member pivotally mounted near its middle. Transverse loads or bending moments between the riser and ship are coupled therebetween at the lower end of the guide tube 24, at the spherical member 21, and at the upper end of the riser adjacent the draw bar 28. By so distributing the loads, extreme bending moments on the riser at the gimbal support are avoided.

Additional structural details of the guide tube and its mounting to the spherical member 21 are illustrated in FIGS. 2 and 3. As the ship heaves the riser must travel along the length of a guide tube 24 and therefore contoured rubber rollers 47 and 48 (not shown in FIG. 1) are rotatably mounted transverse to the tube axis at the upper and lower ends, respectively, of the guide tube. In the illustrated embodiment a set of four concave rollers 47 contoured to mate with the outside of the riser are mounted at the upper end of the guide tube in a multiple pillow block 49 which is bolted to a flange 51 on the upper end of the guide tube. A similar pillow block 52 fastened to the opposite lower end of the support tube journals the contoured rubber rollers 48 at that end. The guide rollers 47 which may be segmented, if desired, to minimize friction are contoured so as to closely engage the periphery of the cylindrical riser and thereby permit free relative motion of the riser along the length of the tube as the ship rises and falls. Transverse loads by the riser on the guide tube 24 are transmitted thereto only by way of the rollers 47 and 48 at the ends of the guide tube.

It will also be apparent that if the guide tube 24 is fixed relative to the tower which rotates as the ship weathervanes, the riser must apparently rotate about an axis along the length of the guide tube. Friction of the contoured rubber rollers 47 and 48 bearing on the riser effectively prevent relative rotation between the riser and the guide tube. Therefore a pair of conventional ball bearings 53 are provided between the guide tube and the spherical member 21 so that the entire guide tube can rotate about its axis relative to the spherical member 21 and the tower, and yet transmit a substantial transverse load to the spherical member. O-ring seals 55 are provided between the spherical member and a sleeve 56 which is interposed between the upper bearing 53 and a flange 57 on the upper end of the guide tube. The sleeve 56 extends along the length of the guide tube to a position just beyond the spherical

member 21 where a ring 58 is bolted on so as to support the lower ball bearing 53. Additional O-ring seals 59 are also provided at the lower end of the sleeve to prevent water from entering the ball bearings.

5 The bearing support system between the spherical member 21 and the guide tube 24 assures that the guide tube is free to rotate with the riser relative to the spherical member about an axis along the length of the tube; however, any transverse loads are readily transmitted between the guide tube and the spherical member.

10 Referring again to FIG. 1 it will be apparent that as the ship rolls, for example, with the tower and riser in a substantially fixed position a bending moment is applied by the riser to the lower end of the guide tube 24 and to the tower at the draw bar 28 with both of these bending moments tending to pivot the combined tower and guide tube in a clockwise or counter clockwise direction about the tower support gimbals. Since the load tending to cause tilt of the tower is applied at points both above and below the tower gimbals the stress on the riser is minimized. In the illustrated arrangement of FIG. 1 the upper end of the riser is near its maximum vertical extent and the bending moment which would be applied to the tower alone in the absence of a guide tube would probably be sufficient to tilt the tower without creating undue stress in the riser 15 at the spherical member 21. It will be apparent, however, that when the riser head and draw bar are at their lower extent within the tower, the moment arm between the top of the riser and the tower gimbals would be short and the stresses required for tower tilting would be significantly higher. It is in this lower position that the guide tube is of maximum significance.

20 It will be apparent that many modifications and variations of the present invention are possible in light of the above teachings; thus, for example, a structural framework rather than the guide tube could be employed between the spherical member and the riser at a point substantially below the spherical member. Other modifications and variations would readily suggest themselves to one skilled in the art.

35 What I claim is:

1. In combination:

40 a ship having a mooring plug extending vertically through the ship,
bearing means disposed between said plug and said ship to allow said plug to rotate relative to said ship,
said mooring plug having a vertically disposed opening,
a riser tower support bearing mounted to said plug within said opening to allow said support to rotate with respect to said plug,
45 a riser tower gimbaled to said tower support to allow said riser tower to nutate and rotate with respect to said plug means on said plug adapted to receive anchor chains so that said ship may weather vane around said plug,
guide cable means extending from the deck of said ship to said tower to maintain said tower in a substantially vertical position, and substantially nonrotational with respect to the deck,
a riser extending up through said opening, and
50 swivel means for connecting the upper end of said riser to said tower so that said tower may rotate with respect to said riser.

55 2. In the combination of claim 1 wherein:

a rigid tubular guide is rigidly dependently from said tower and disposed around said riser to limit the bending stresses in said riser.
